L. W. REEPS

DRYING FORM

Filed July 12, 1922

WITNESS:

Robt. R. Pritchel

FIG. 3.

Leroy W. Reeps

BY
Frank S. Bunn

ATTORNEY.

INVENTOR

UNITED STATES PATENT OFFICE.

LEROY W. REEPS, OF SPRINGFIELD, PENNSYLVANIA, ASSIGNOR TO PHILADELPHIA METAL DRYING FORM COMPANY, OF PHILADELPHIA, PENNSYLVANIA, A CORPORATION OF DELAWARE

DRYING FORM.

Application filed July 12, 1922. Serial No. 574,358.

To all whom it may concern:

Be it known that I, LEROY W. REEPS, a citizen of the United States, residing at Springfield, county of Delaware and State 5 of Pennsylvania, have invented a new and useful Improvement in Drying Forms, of which the following is a full, clear, and exact description, reference being had to the accompanying drawings, which form a part of 10 this specification.

This invention relates to an improvement in drying forms for wearing apparel, and more particularly relates to steam heated metal drying forms for drying hosiery, etc.

15 I am aware that hollow, steam heated metal drying forms for hosiery, gloves, etc., which are heated by steam supplied to the interior thereof, are old in the art, but in all such forms known to me, the forms are 20 fixedly mounted on a suitable support so that it is quite difficult for the operator to inspect all portions of the article on the form.

25 The object of my invention is to provide a form of this character which can readily be turned on its support so that the operator can readily inspect all portions of the article without substantially changing her position in front of the form.

30 The precise nature of my invention will be best understood by reference to the accompanying drawings, it being premised, however, that changes may be made in the details of construction without departing from the spirit and scope of my invention as defined in the appended claims.

35 Fig. 1 is a side elevation, partially in section, of one type of form made in accordance with my invention.

40 Fig. 2 is a similar view of a slightly modified form.

Fig. 3 is a vertical section through the connection between the form and its support.

Fig. 4 is a sectional plan view in the line 4-4 of Fig. 3.

45 Fig. 5 is a detail sectional view of a modified form of support.

Fig. 6 is a detail plan view of the clamp stop.

50 In these drawings, the reference character *a* designates the drying form, which in this case is shaped for drying ladies' hose, and which is formed of two blanked metal plates which are then bent to shape and after-

wards welded along their edges to form steam-tight joints. Secured to the lower end 55 of the form *a* is a tube *b* having a flange *c* near the lower end thereof. This flange may be secured to the tube in any desired manner and is seated on an internal flange *d* in a tube *e* extending upwardly from a pipe *f*. 60 Surrounding the tube *b* above the flanges *c* and *d* is a gland *g* having a screw-threaded engagement with the interior of the upper end of tube *e*. Interposed between flange *c* and the lower end of the gland *g* is a 65 metal washer *h* and steam packing rings *i*. The packing rings are compressed between the washer *h* and gland *g*, to form steam-tight joints between the packing and tubes 70 *b* and *e*, and at the same time permit tube *b* to be turned in tube *e*. The weight of form *a* is supported on flange *d*, while flange *c* is adapted to rotate between flange *d* and washer *h*, the latter of which will prevent 75 the cutting of the packing *i* by the flange *c* when the form is turned, and will reduce friction between the parts. The tube *b* is journaled in the bore of gland *g* and flange *d*. *j* is a stop connected to the upper end of tube *e* and is formed on one member of a 80 split clamp *k*. The upper end of stop *j* extends into the plane of the form *a* and is arranged to prevent the form being rotated in either direction beyond predetermined limits, and thereby prevent the forms from fouling 85 with other forms adjacent thereto.

Located within pipe *f* is a second pipe *l* having an upwardly extending nipple *m* concentric with tubes *b* and *e*, and which telescopically engages the lower end of a 90 tube *n*. The tube *n* extends upwardly into the interior of the form *a*, and preferably to the upper end thereof as indicated in Fig. 1, and is open at both ends to permit the passage of steam therethrough, as hereinafter described. This tube is preferably fixedly secured to the form *a*, and preferably extends upwardly through the central portion thereof, and forms a spacer or support for preventing the indentation of the form- 100 forming sheets.

In the drawings, I have merely shown one form *a* supported from the pipe *f*, but in practice there are a series of such forms supported from the pipe. Each form is connected to pipes *f* and *l* in the manner shown, 105

and pipes *f* and *l* are provided with valves for controlling the admission of steam to pipe *l* and outlet of water condensation or steam and water from pipe *f*.

5 In operation, the steam passes from pipe *l*, through pipe *n*, downwardly through the form *a* on both sides of pipe *n* to the pipe *f*, through tubes *b* and *e*.

In the device shown in Fig. 2, the form is 10 provided with the usual partition member and support *p*. Where the device is provided with a partition member such as *p*, it is only necessary to extend pipe *n* a short distance upwardly in the form on one side 15 of the partition. In this form, the steam passes up one side of the partition and down the other, but in both forms the steam delivery pipes are surrounded by the outgoing wet steam so that no portion of the outer 20 surface of the inlet conduits for the steam is in contact with the atmosphere, but are surrounded by the outgoing steam. This prevents the condensation of steam in the inlet conduits, as the inner and outer walls 25 are directly in contact with the steam and also provides means for conducting all the water of condensation from the forms to the outlet pipe or conduit.

In the form shown, the flange *c* is fixedly 30 brazed or welded to tube *b* so that it is necessary to assemble the parts on tube *b* before welding the flange to the tube *b* or welding the tube *b* to form *a*.

If desired, the flange may be removably 35 secured to the tube as indicated in Fig. 5, in which the flange *c'* is provided with an internally threaded extension member into which is threaded the end of tube *b'*. The flange may be secured against rotation by a 40 through pin or a screw *c*², as shown.

In this case, the outer surface of the extension of the flange is turned to rotate within the supporting flange in tube *e*.

The advantages of my invention result 45 from the provision of an internally heated form, which is adapted to turn on its support.

Further advantages result from the provision of such a form in which the steam is 50 conducted to the interior of the form through an inlet tube, and which is so arranged that all water of condensation from the form will pass to an outlet conduit, and thereby prevent water of condensation passing from the forms to the steam inlet pipe.

Having now fully described my inven-

tion, what I claim and desire to protect by Letters Patent is:

1. A hollow drying form having concentric inlet and outlet tubes connected thereto, 60 concentric inlet and outlet conduits telescopically connected to the inlet and outlet tubes, a flanged connection between the outer tube and the outer conduit arranged to permit free rotation of the tubes with relation to the conduits but to prevent axial 65 movement of the tubes relative to the conduits, and a stuffing box in said connection to form a steam-tight joint between the outer tube and the outer conduit. 70

2. A hollow metal drying form having a tube connected to the lower end thereof, a conduit, a tube extending from the conduit, there being a steam-tight swivel joint connecting said tubes to each other, a second 75 tube supported from the form within the first tube on the form, a conduit within the first conduit, and a nipple connected to the second conduit having a telescopic connection with the second tube supported from 80 the form.

3. A hollow metal drying form having a tube connected to the lower end thereof, a conduit, a tube extending from the conduit, there being a steam-tight swivel joint connecting said tubes to each other, a second tube supported from the form within the first tube on the form, a conduit within the first conduit, a nipple connected to the second conduit having a telescopic connection 90 with the second tube supported from the form, and a stop for the form arranged to prevent said form being turned more than 360°. 95

4. A drying system comprising a steam inlet conduit, a return conduit, one conduit being within the other conduit, a nipple extending from each conduit, the one nipple being within and concentric with the other nipple, a hollow drying form having two 100 concentric tubes extending therefrom and telescopically engaging the nipples, and a flanged steam-tight joint between the outer nipple and the outer tube arranged to permit the form to be turned freely about the 105 axes of the tubes and nipples but to prevent axial movement of the nipples and tubes.

In testimony of which invention, I have hereunto set my hand, at Philada, Penna, on this 10th day of July, 1922.

LEROY W. REEPS.
